DOUBLE-ACTING RECIPROCATING PUMP

Henry M. McNew, Milwaukee, Wis., assignor of
one-half to Michael Scarpace, Milwaukee, Wis.

Application February 20, 1939, Serial No. 257,342

2 Claims. (Cl. 103—175)

This invention appertains to pumps and compressors, and more particularly to an improved double-acting reciprocating pump for delivering a constant noninterrupted flow of fluid to its outlet on both strokes of its piston.

One of the primary objects of my invention is to provide a double-acting reciprocating pump constructed in such a manner that the various parts thereof, such as pipes, joints, check valves, etc., are formed from standard parts found in the open market, whereby the pump can be conveniently and economically kept in good running condition.

Another important object of my invention is to provide a novel means for guiding the pump or piston rod in the cylinder, whereby the same will not interfere with the intake or expulsion of fluid, the coupling for the intake and exhaust at one end of the cylinder forming said piston rod guide.

A further salient object of my invention is to provide a double-acting reciprocating pump of the above character, which will be durable and efficient in use, one that will be simple and easy to manufacture, and one which can be placed upon the market at a reasonable cost.

With these and other objects in view, the invention consists in the novel construction, arrangement, and formation of parts, as will be hereinafter more specifically described, claimed, and illustrated in the accompanying drawing, in which drawing:

The figure is a side elevational view of my improved pump, with parts thereof broken away and in section to illustrate structural details.

Referring to the drawing in detail, the letter P generally indicates my improved pump, and the same may include a suitable base 1 formed from a casting or in any other desired way. The base 1 adjacent one end is provided with a support 2 on which is fitted the cylinder 3. The cylinder 3 could be formed from a length of pipe of the desired size and constructed from the preferred material, and, as shown, the ends of the cylinder 3 are fitted in annular grooves 4 in end cylinder heads 5 and 6. These cylinder heads are secured to the support 2 of the base 1 through the use of removable machine bolts 7. The heads 5 and 6 are also connected together by longitudinally extending bolts 8 disposed around the cylinder.

Reciprocally mounted in the cylinder is a piston 9 carrying suitable leather cups 11 and 12, which can be held thereon in any desired way. Rigidly secured to the axial center of the piston 9 is a piston or pump rod 13, which extends outwardly

through the cylinder head 6 beyond the cylinder.

Obviously, the piston or pump rod 13 can be actuated in any preferred manner, and, as shown, a hand operating lever 14 is provided. The lower end of the lever is rockably mounted upon a cross shaft 15 mounted in suitable bearings carried by the base 1. The lever, at a point intermediate its ends, is provided with slots 16 through which extend bearing pins 17 carried by the piston rod. The bearing pins can carry anti-friction rollers for engagement with the walls of the slots 16, if such should be preferred. An upright 18 can be formed on the base beyond the lever, and the upper end of this upright can have formed thereon a guide bearing 19 for the pump or piston rod 13. Threaded into the cylinder head 5 is a short length of pipe 20, which forms the inlet and exhaust for fluid for one end of the cylinder. This short length of pipe 20 has threaded thereon a T-coupling 21, and the opposite arms of the coupling have threaded therein pipe sections 22 and 23, which, in turn, carry check valves 24 and 25. Connected with the outer ends of the casings of the check valves 24 and 25 are short lengths of pipes 26 and 27, which carry elbow couplings 28 and 29, the purpose of which will be later set forth.

Threaded into the axial center of the cylinder head 6 is a short length of pipe 30 of a greater diameter than the pipe 20, and this pipe 30 has threaded thereon a coupling 31 of a cruciform. The opposite arms of the coupling 31 have threaded therein reducing nipples 32 and 33, which receive short lengths of pipe 34 and 35, which, in turn, carry the check valves 36 and 37. The outer ends of the casings of the check valves 36 and 37 have threaded therein short lengths of pipe 38 and 39, and these pipe lengths 38 and 39 carry T-couplings 40 and 41. One arm of the coupling 40 is connected to the elbow coupling 28 by a length of pipe 42. The T-coupling 41 is connected to the elbow coupling 29 by a length of pipe 43. If desired, the pipe lengths 42 and 43 can be formed in sections and connected together by turnbuckle pipe couplings 44. The outer arm of the T-coupling 40 has connected thereto the outlet pipe 45, which leads to a suitable point of delivery. The outer arm of the T-coupling 41 has connected thereto the inlet pipe 46, which leads to a suitable source of liquid supply.

Particular attention is invited to the fact that the piston or pump rod 13 extends through the relatively large pipe length 30 and the coupling 31, as this forms an exceptionally simple fitting.

and allows the simple and efficient guiding of the pump rod without interfering with the intake and exhausting of fluid. The coupling 31 has its outer arm formed as a guide for the piston or pump rod, and a suitable packing gland 47 is carried by the coupling for said rod.

In view of the fact that the pipe 30 is of a greater diameter than the pipe 20, the free flow of fluid through the pipe 30, without interference 10 from the piston rod, is assured, and, further, the piston rod will not take up any active part of the cylinder, as the capacity of the cylinder adjacent the cylinder head 6 is slightly increased by said pipe length 30.

15 All of the check valves 24, 25, 36, and 37 open in the same direction. Thus, the check valves 25 and 37 open toward the cylinder, while the check valves 24 and 36 open away from the cylinder. Considering that the piston 9 is moving toward the right, then the piston will be creating a suction within the pipe 20. This suction will cause the closing of the check valve 24 and the opening of the check valve 25, and the intaking of fluid from the intake pipe 46. 20 Suction in the pipe 46 will hold the check valve 37 on its seat. Fluid in front of the piston will be forced out of the cylinder under pressure through the pipe 30 and coupling 31, and this pressure will also tend to hold the check valve 30 37 on its seat, and will force open the check valve 36, and fluid will be delivered to the outlet pipe 45. This pressure will also tend to hold the check valve 24 on its seat.

As the piston 9 moves toward the left, the 35 fluid will be expelled through the pipe 20 and the coupling 21, and this pressure will hold the check valve 25 on its seat and will move the check valve 24 off its seat, and liquid under pressure will flow through the outlet pipe 45. This liquid under 40 pressure will also hold the valve 36 on its seat. Movement of the piston 9 to the left will cause a suction in the pipe 30, and this suction will also tend to hold the check valve 36 on its seat, and will lift the check valve 37 off its seat, and liquid 45 will be drawn into the right-hand end of the cylinder through the inlet pipe 46.

In order to prevent the striking of the leather cup 12 against the cylinder head 6, the piston or

pump rod 13 can loosely carry a perforated disc 48. Liquid will readily flow through the apertures in the disc, and the disc is of such a thickness as to act as a stop between the cylinder head 6 and the piston to prevent the contacting of the 5 cup washer 12 with said cylinder head 6.

Changes in details may be made without departing from the spirit or the scope of my invention, but what I claim as new is:

1. A pump comprising, a base, cylinder heads 10 secured to the base, a cylinder confined between said heads, a pipe connected to one head, a pipe connected to the axial center of the other head having a greater diameter than the first-mentioned pipe, couplings connected to said 15 pipes, check valves communicating with the opposite arms of said couplings, an intake pipe on one side of the cylinder communicating with certain check valves, and an outlet pipe on the other side of the cylinder communicating with 20 certain other of the check valves, a piston in said cylinder, a piston rod connected to the piston and extending through the pipe section of relatively great diameter and the coupling carried thereby, a packing gland and guide for the piston 25 rod carried by said last-mentioned coupling, a guide on the base arranged in spaced relation to the combined packing gland and guide for receiving the outer end of the piston rod, and means for actuating the piston rod operatively 30 connected thereto between the last-mentioned guide and the combined packing gland and guide.

2. In a pump, a cylinder, a cylinder head, an axially disposed guide and main liquid inlet and outlet pipe communicating with the head, a 35 stuffing box on the outer end of the pipe, a piston reciprocally mounted in the cylinder, a piston rod secured to the piston and extending through the head, pipe, and stuffing box, valve-controlled inlet and outlet pipes communicating with the guide and main liquid inlet and outlet pipe between the head and the stuffing box, and a perforated buffer disc loosely mounted on the piston rod between the piston and the head to permit the free flow of liquid therethrough, said 40 disc being of a greater size than the guide and main liquid inlet and outlet pipe.

HENRY M. McNEW.
